ATTORNEY

UNITED STATES PATENT OFFICE

AUGUSTA M. BERGER, OF BROOKLYN, NEW YORK

SHOE LACE FASTENER

Application filed September 11, 1931. Serial No. 562,363.

This invention relates to a shoe lace fastener.

Lace shoes are the most comfortable form of foot wear as they permit of easier adjustment in the event of changes in the size of the foot occasioned by the weather or the physical condition of the user. The lace shoe, however, has not the neat appearance of the button shoe and in many cases such as 10 in children, crippled individuals and stout persons is annoying as the lacing ends frequently become untied which are annoying and may be dangerous due to the possibility of stepping on the loose ends or catching them in some obstruction.

One of the objects of this invention is to provide means that are easily manipulated and neat in appearance to securely hold the free ends of a shoe lace. A further object 20 of this invention is to provide means for holding the loose ends of the bow knot to prevent it from becoming united.

A still further object of the invention is to provide a device that will increase the 25 neatness in appearance of a laced shoe.

Referring to the drawing:

Figure 1 is a view in elevation of a device embodying the principles of my invention showing the same attached to a shoe.

30 Figure 2 is an enlarged plan view of a device embodying the principles of my invention in an open view.

Figure 3 is a cross sectional view of Figure 2 along the line 3, 3, looking in the direction 35 of the arrows.

Figure 4 is a plan view of a modified form of device.

Figure 5 is a sectional view of Figure 4 along the line 5, 5.

40 Various attempts have been made in connection with lace shoes for a device to securely hold the loose ends of the shoe laces. Such a device must be small and capable of automatic adjustment to provide for the 45 varying thickness of the loose ends. In addition, it must be easily manipulated.

In carrying out my invention, I propose to provide a device which is at the same time small, easily manipulated, of neat appearance and one which will satisfactorily and

securely hold the loose ends of the shoe laces. The device is formed out of sheet metal having a body portion 1 which may be circular, oval or any desired shape having two integral loops or hooks 2 oppositely positioned with respect to body portion 1. 55

Although I have shown members 2 in the form of hooks, one of said members might be closed about yielding member 3 if desired, but I preferably prefer members 2 as shown 60 as it permits of replacement of yielding member 3 in the event of wear. Body portion 1 may be secured to the shoe in any well known manner such as by an eyelet passing through central opening 4, the heads of the eyelet bearing against body portion 1 surrounding opening 4 and the inside of the shoe. That is, the eyelet is compressed to hold body portion 1 against the shoe upper 6 adjacent the top thereof. Other well known forms of fastening might be used such as metallic prongs 65 integral with body portion 1 which may be pushed through the leather and then upset or bent over to secure same to the shoe upper 6. Yielding member 3 is preferably formed 70

of rubber with a covering of the same color as the shoe. This covering may be silk or cotton or other material woven in such a fashion as to permit of the extension and contraction of the rubber body. Various 75 substitutes for the yielding member 3 might be used and still fall within the scope of my invention. For instance, in Figures 4 and 5, I have shown a cylindrical spring 3' secured to bar 5. Bar 5 is adapted to engage 80 with hook 2' and permits of easier engagement and removal as well as a more secure 85 method of fastening than a circular coiled spring.

In the modified form, I propose to coat 90 with enamel or other material, spring 3', of the same color as the shoe on which it is placed. The operation of the device is as follows:

The wearer of the shoe laces the shoe in the 95 normal manner, ties the usual bow knot, places the ends 7 thereof between members 2, 2, across body portion 1 with one hand and with the other snaps yielding member 3 over the shoe lace ends into members 2, 2. To untie 100

the shoe the wearer slips yielding member 3 from either member 2, 2, and removes the ends of the shoe laces from between members 2, 2, and then unties the laces. Members 5 2, 2, are sufficiently contracted to retain yielding member 3 from falling and of engagement therewith and to prevent the disengagement of member 3 from one of the members 2 when the shoes are not in use. Body portion 1 is 10 therefore made of a resilient material to permit of members 2, 2, functioning both as retaining members for yielding member 3 and as latches to maintain member 3 in engagement therewith.

15 What I claim is:

1. A shoe lace fastener comprising a metallic body portion of resilient material, means for securing the body portion to the shoe upper, said body portion having two 20 curved members integral therewith, a yielding member adapted to be removably secured within said two curved members to compress between said yielding member and said body portion the loose ends of the shoe laces.

25 2. A shoe lace fastener comprising a resilient metallic body portion having two curved members integral therewith and forming hooks, a yielding member adapted to be engaged by said hooks to retain the loose ends 30 of a shoe lace between the yielding member and the body portion when said yielding member is in engagement with said hooks, the opening of said hooks being slightly less than the diameter of the yielding member to prevent accidental removal of the yielding member 35 from the hooks.

Signed at New York in the county of New York and State of New York this fifteenth day of July A. D. 1931.

40 AUGUSTA M. BERGER.
